UNITED STATES PATENT OFFICE.

WILLIAM A. DOREY, OF NEWARK, OHIO, ASSIGNOR TO HOLOPHANE GLASS COMPANY, OF NEW YORK, N. Y., A CORPORATION OF NEW JERSEY.

LUMINAIRE.

Application filed October 28, 1924. Serial No. 746,272.

The object of the present invention is to secure a distribution of light elongated in the direction of the hallway so that units can be spaced widely apart without sacrificing uniformity and without wasting too much light on walls and corridor. I accomplish this by applying a special bowl arrangement to a bowl-type luminaire, in which a central area of the bowl is given an exact and definite limit or boundaries which will permit transmission of all light within the boundaries to be illuminated which can be obtained in that way without means for lateral deviation.

15 The problem in all corridor lighting is to have the luminaires close to the ceiling and to have a fairly uniform brightness down through the corridor.

20 To obtain this with a symmetrical distribution of light around a vertical axis it is necessary to place an unusual number of luminaires close together on account of the fact that the corridors are relatively narrow, or else if few units are used, they must be spaced widely apart and the light must be thrown out at a wide angle so that a great proportion of it will be caught by the side walls instead of distributed in useful directions; moreover, if uniform illumination is secured on the floor of the corridor a succession of bright spots is usually found on the walls, a pair for each unit giving an uneven appearance.

35 Fig. 1 is a plan view of the interior surface of a refracting bowl employed in my invention shown in diagrammatic form, and

Fig. 2 is a vertical cross section in the plane 2—2 of Fig. 1 showing the interior only, also in diagrammatic form,

40 Figs. 3 and 4 are diagrammatic views of a typical corridor showing the luminaires in exaggerated scale.

45 Fig. 5 is a vertical cross section in a plane parallel to the hall, of a complete form of my device showing the relation between light source, reflector and bowl.

50 The various parts of the device are shown in Fig. 5 which is a vertical cross section in the plane of the center line of the corridor. 7 is the light source, and 8 is a reflector having on its outer surface double reflecting prisms, 9 is the lower bowl having horizontal refracting prisms 10 covering its exterior and adapted to transmit light re-

flected from the reflector and light received 55 direct from the source. The more distinctive part of the invention, the lower bowl, is shown in diagrammatic form in Figs. 1 and 2.

For the purpose of explaining the invention I have assumed a given set of conditions of mounting heights and width of corridor and determined the intercept of the various cones of light with the dividing line between floor and walls. This intercept may then be 60 translated to the surface of the prismatic bowl 9 by laying off the angle of the arc useful in lighting the floor for each cone along the surface of the horizontal prism which delivers its light rays in that cone. 65 These intercepts when translated to the bowl are shown in Figs. 1 and 2, as lines 1—3—4, and 1' 3' 4', which divide its surface into three sections, 6, 5, 6' which will be symmetrical to a straight line through 70 the axis, parallel to the walls of the corridor. The central section 5 will be a strip extending across the whole surface of the bowl, and its area in proportion to the whole and also the contour of the intercepts will 75 be determined very definitely by the installation conditions assumed, by the shape of the bowl and by the form of distribution of light in vertical planes from the horizontal prisms.

80 Line 2—2 in Fig. 1 divides the outer sections 6 and 6' into two halves which are provided with prisms deflecting the light oppositely. Each half section deflects the light toward the adjacent portion of the central 85 section.

85 If the interior of the refracting bowl be of smooth glass all of the light emitted by the central section 5 as described above will pass direct to the floor of the corridor, without in the line of division formed by the walls, and all of the light emitted by the two outward sections 6 and 6' will be transmitted to the side walls. In my construction I prefer to keep this central section smooth on the 90 interior or provided with very shallow radial flutes or roughened surfaces merely giving sufficient spread to do away with sharp filament images. In the two outer sections 6 and 6' I use radial refracting 95 prisms or flutes designed to deviate the light laterally so that it will fall to a large degree 100 within the limits of the floor or will strike 105

the side walls at points intermediate between two luminaires and thus promote uniformity of illumination of the side walls.

Figs. 3 and 4 are diagrammatic views of the corridor showing the luminaires in exaggerated scale, so as to show the setting of the central section 5 and the outer section 6 and 6' with reference to the conditions of the installations.

Fig. 3 is a diagrammatic vertical cross section of a typical corridor in a plane at right angles to the hall. 11 and 11' are light rays issuing from the extreme boundaries of the area 5 and delivered at the junction between walls and floor. Now if you consider any slanting cross section of the corridor the light rays emitted in that cross section from the boundaries of the area 5 will be delivered at the junction between walls and floor, the boundaries of area 5 having been shaped to take care of the change in angular relation between the limiting rays similar to 11 and 11'.

Fig. 4 is a diagrammatic plan of a portion of a corridor. 12 and 12' are projections of the path of the light rays issuing from the extreme boundaries of the area 5 and delivered midway between units at the junction between walls and floor. If these be extended they will pass through the center of the plan of the luminaire because they have not been subject to lateral deflection. 13 and 13' are projections of the path of typical light rays issuing from areas 6 and 6' and delivered at the same points as 11 and 11'. If these be extended they will not pass through the centre of the plan of the luminaire because they have been subjected to a lateral deflection. In general the area 5 lays down a light pattern substantially coincident with a unit portion of the floor having its centre at the luminaire and the areas 6 and 6' deflect the light rays laterally in the direction of the longest dimension of this unit floor portion so as to increase the light on the floor, soften the edges of the light pattern and reduce the light on the walls directly opposite the units.

In other words, having been given an area to be illuminated, at a prescribed mounting height and with a certain shape of bowl giving a definite distribution of light, the contour between the plain and prismatic parts becomes absolutely fixed. Theoretically, any change in (1) the width of the hall, (2) the mounting height, (3) the vertical distribution of the unit or (4) the contour of the bowl will involve some change in the shape of this central area. The prismatic radial areas are adjusted accordingly.

I have shown the unit as being entirely composed of prismatic glass but it should be understood that any reflecting material can be employed in the upper portion and that the lower glass bowl may have deflect-

ing areas of any character abutting a comparatively translucent area for the purpose herein specified.

While I have shown and described the invention with reference to corridor lighting, the form of construction is equally useful in street lighting installations and similar service, the walls of the houses and street taking the place of the walls and floor of the corridor, and in these installations it may be found desirable to use double glassware in which the prismatic construction is entirely contained between covers smooth on the outside and inside.

I claim:

1. A luminaire for corridor lighting comprising a light source, and bowl forming a unit enclosing the source, the bowl having a central area with its major axis paralleling the side walls of the corridor and comparatively denser adjacent areas.

2. A luminaire for corridor lighting comprising a light source, a reflector and bowl forming a unit enclosing the source, the bowl having a central area with its major axis paralleling the side walls of the corridor and comparatively denser adjacent areas.

3. A luminaire for corridor lighting, comprising a light source, a reflector and bowl forming a unit enclosing the source, the bowl having a central area with its major axis paralleling the side walls of the corridor and adjacent areas adapted to direct light rays to the floor within the limits of the side walls.

4. A luminaire for corridor lighting comprising a light source, a reflector and bowl forming a unit enclosing the source, the bowl having a comparatively non-deflecting central area with its major axis paralleling the side walls of the corridor and adjacent areas adapted to direct light rays towards the floor within the limits of the side walls.

5. A luminaire for corridor lighting comprising a light source, a reflector and bowl forming a unit enclosing the source, the bowl having a translucent central area with its major axis paralleling the side walls of the corridor and comparatively denser adjacent areas adapted to direct light rays towards the floor within the limits of the side walls.

6. A luminaire for corridor lighting comprising a light source, a reflector and bowl forming a unit enclosing the source, the bowl having a comparatively non-deflecting central area with its major axis paralleling the side walls of the corridor and adjacent areas provided with radial refracting corrugations adapted to direct light rays towards the floor within the limits of the side walls.

7. A luminaire for corridor lighting comprising a light source, a reflector and bowl forming a unit enclosing the source, the

- 5 bowl having on its interior surface a comparatively non-deflecting central area with its major axis paralleling the side walls of the corridor and adjacent areas provided with radial refracting corrugations adapted to direct light rays towards the floor within the limits of the side walls.
8. A luminaire for corridor lighting comprising a light source, a reflector and bowl 10 forming a unit enclosing the source, the reflector having double reflecting prisms on its outer surface, and the bowl having on its interior surface a central area within its major axis paralleling the side walls of the corridor and adjacent areas provided on their inner surfaces with radial refracting corrugations adapted to direct light rays towards the floor within the limits of the side walls.
- 15 9. A luminaire for corridor lighting comprising a light source, and a bowl enclosing the source, the bowl having a comparatively non-deflecting central area with its major axis paralleling the side walls of the corridor and adjacent areas provided with radial refracting corrugations, the plain area 20 being limited to that portion of the surface adapted to emit light rays to the floor of the corridor within the limits of the side walls and the corrugated areas being adapted to deflect light rays laterally towards the floor.
- 25 10. A luminaire for corridor lighting comprising a light source, and a bowl enclosing the source, the bowl having on its interior surface a comparatively non-deflecting central area with its major axis paralleling the side walls of the corridor and adjacent areas provided with radial refracting corrugations, the plain area 30 being limited to that portion of the surface adapted to emit light rays to the floor of the corridor within the limits of the side walls and the corrugated areas being adapted to deflect light rays laterally towards the floor.
- 35 40

11. A luminaire for corridor lighting comprising a light source, a reflector and bowl forming a unit enclosing the source, the bowl having on its interior surface a comparatively non-deflecting central area with its major axis paralleling the side walls of the corridor and adjacent areas provided with radial refracting corrugations, the plain area being limited to that portion of the surface adapted to emit light rays to the floor of the corridor within the limits of the side walls and the corrugated areas being adapted to deflect light rays laterally towards the floor.

12. A luminaire for corridor lighting comprising a light source, a reflector and bowl forming a unit enclosing the source, the bowl having a central area with its major axis paralleling the side walls of the corridor and adjacent areas provided with radial refracting corrugations, the central area being limited to that portion of the surface adapted to emit light rays to the floor of the corridor within the limits of the side walls and the corrugated areas being adapted to deflect light rays laterally towards the floor.

13. A luminaire for corridor lighting comprising a light source, a reflector having double reflecting prisms on its outer surface and a bowl forming a unit enclosing the source, the bowl having a central area with its major axis paralleling the side walls of the corridor and adjacent areas provided with radial refracting corrugations, the central area being limited to that portion of the surface adapted to emit light rays to the floor of the corridor within the limits of the side walls and the corrugated areas being adapted to deflect light rays laterally towards the floor.

Signed at New York, in the county of New York and State of New York, this 27th day of October 1924.

WILLIAM A. DOREY.
